INVENTOR

Elliott Clemence,

BY

Harold D. Penney, ATTORNEY

UNITED STATES PATENT OFFICE.

ELLIOTT CLEMENCE, OF NEW YORK, N. Y., ASSIGNOR TO MONOWATT CORPORATION, OF NEW YORK, N. Y., A CORPORATION OF NEW YORK.

HEATER PLUG.

Application filed August 12, 1926. Serial No. 128,814.

- This invention has reference to an electric connector, known as an armored heater connector; and which device generally, is in the form of two moulded complements of insulating material, brought together with sockets at the meeting portions, enclosing terminals, and which complements are usually secured together by one or more bolts passing therethrough.
- 10 The object of the present invention is to provide a protective armor and locking or securing means at the outer end of the moulded complements, which not only assist in holding the same together, but will also prevent the splitting or breakage thereof.

A further object of the invention is to provide an end enclosing housing for this purpose, arranged to retain and position the bolt nut and conceal the same, and which will further provide a countersunk mounting for the bolt or screw head, thereby providing a substantially flush and smooth end closure.

A further object of this invention is to provide means on the complementary moulded pieces, whereby, when the metal armor piece is slidably mounted thereon, the armor piece will automatically cause the two complements to be forced together in a rigid manner, thereby causing the armor and the molded elements to be held together in rigid assembly.

In the accompanying drawing showing one embodiment of my invention,

Figure 1 is a front elevation of the assembly.

Figure 2 is a longitudinal section.

Figure 3 is one of the moulded complements with armor removed,

Figure 4 is a side view of one moulded complement or element,

Figure 5 shows the elements assembled before application of the armor from the reverse side.

Figure 6 is a partial section enlarged of one element and the armor in the act of sliding on to operative position.

Figure 7 shows an end view of the armor.

Devices of this character are usually composed of a pair of substantially duplicate complements of moldable dielectric composition, such as 7 and 8, which have recessed portions on their meeting faces to contain suitable electrical contacting and terminal members, not herein shown. One end such as 9 is generally enlarged for receiving wire

connecting terminals, and a supporting coil spring, not shown but well known in this art. These moulded complements are usually held together by a pair of bolts such as 10 and 12, passing through suitably located holes B in the complements. The bolt 12 is usually placed adjacent the outer end thereof.

Where these bolts alone are employed without reinforcement, rough handling, dropping, etc., in addition to the strain of bolt tension tends to fracture or break the insulation, and become dangerous to use. To overcome this difficulty I provide a locking and reinforcing armor member, in the form of an oval, beaded ferrule 13 of suitable metal, with the end portions slightly beaded or rounded as at 14. The two complements have their armor ends 15, 15, slightly reduced and the armor piece or ferrule 13, is made to have a snug fit on the contacting complements at these portions 15, as indicated in Figs. 1 and 2, and its outer face is preferably flush with the unarmored portion, generally denoted by A, of the complements beyond the armor. This is fully illustrated at Fig. 6.

To assist in causing a compression fit of the armor ferrule when slid upon the complements, I provide one or more suitably tapering ribs 16, 16, two on each armor face of each complement, as indicated in Figs. 3-5. These ribs are preferably made to converge outwardly, so that they will have a wedge and shearing action on the ferrule as it is forced on to the complements, as indicated in Fig. 6.

The edge of the ferrule as it slides on, may have a kind of shearing action and will somewhat reduce the wedge or rib, insuring a tight compression fit between the ferrule and the complements.

The ferrule is provided with an inner cutting edge for shearing the ribs, the pointed end of the ribs shearing most easily, the wide end of the rib offering more resistance to shearing and forcing the cutting edge away from the side face of the reduced ends, whereby the cutting edge shears off the rib to a tight wedging fit irrespective of unavoidable variations in the size of the reduced ends and ribs during manufacture.

This ferrule is arranged to surround and enclose the bolt 12 at this end portion. In one of the complements such as 8, a recessed socket 17 is provided at the opening B for the bolt, preferably of the same contour as

the nut 18, to prevent the nut from turning when the bolt 12 is applied. The nut is placed in this socket before the ferrule is applied, and will be retained in this position by the 5 ferrule.

The other complement 7, at the bore B for the bolt 12 is recessed in the form of an elongated open-sided slot 19, see Figs. 3 and 6. This is to receive the projecting margin of the 10 counterbore 20 in the ferrule 13, as indicated in Fig. 6, and which recess 19 adjacent the bore B will accommodate and receive the counterbored head 21 of the bolt. Since the counterbore 20 projects inwardly, the slot 19 15 will permit the ferrule to be advanced until this opening is opposite the bolt hole; the nut 18 having been previously placed in the socket, the ferrule is slid on until it is flush at the shouldered end of the complements. 20 Then the bolt 12 is inserted in the counterbore 20, and is screwed into the nut held in its socket by the ferrule. The bolt is of such length that the head will engage the counterbore 20 and press this part of the ferrule 25 against the complement 7.

It will be observed that the ribs 16 are on opposite sides of the bolt for each complement, and will insure a tight fit of the ferrule. At the same time the bolt will draw 30 one face of the ferrule into very tight engagement with the complement on this side.

The assembling of this device is very simple and will be understood by the description given. The bolt can be removed at any time, 35 and then the ferrule slid off, giving access to the terminals, and the several parts returned to locked position.

While I have not shown the usual interior electric contacts and terminal connections 40 herein it is understood that they are of any suitable standard type adapted for this purpose.

It is further obvious that an end armoring of similar form may be used by modifying the 45 construction herein, without departing from the scope of the herein appended claims.

Having described my invention, what I claim is:

1. A heater plug of the class described, 50 comprising two molded insulating complements, said complements having reduced ends and bolt receiving means therein, locking bolts in said receiving means and a ferrule adapted to fit over said reduced ends and one 55 of said bolts, shearable rib means between said ferrule and said complements for causing the ferrule and the bolt associated therewith to compress said complements together.

2. In an insulated heater plug of the class 60 described, the combination of dielectric, substantially duplicate ribbed complements, a metal armoring ferrule for compressively holding said complements together at one end thereof, bolt holding means for said complements, a nut socket seat on one of said com-

plements, a counterbore slot in the other of said complements and a ferrule having a counterbored bolt hole therein, said ferrule having a cutting edge thereon for shearing said ribs when the ferrule is slid upon said complements to hold the same in operative assembly. 70

3. An insulated heater plug of the class described, comprising a pair of substantially duplicate ribbed complements, a counterbore 75 bolt receiving ferrule for compressively holding said complements together at one end thereof, bolt holding means for said complements, a nut socket seat on one of said complements and a counterbore ferrule receiving slot in the other of said complements and a ferrule having a counterbored bolt hole therein, said ferrule having a cutting edge thereon for shearing said ribs when the ferrule is slid upon said complements to hold 80 the same in operative assembly, and a bolt passing through said complements and said ferrule to lock the complements together. 85

4. A plug comprising a pair of complements; means including a pair of members 90 holding said complements together; and a device held on an end of said plug by one of said members and hiding and holding in place the other member.

5. A plug comprising a pair of complements; means including a pair of members holding said complements together; and a ferrule held on an end of said plug by one of 95 said members and hiding and holding in place the other member. 100

6. A plug comprising a pair of complements; means including a nut member and a bolt member holding said complements together; and a ferrule held on an end of said plug by one of 105 said members and hiding and holding in place the other member.

7. A plug comprising a pair of complements; said plug having a bolt hole provided with a nut-receiving end-socket and passing through the complements; a ferrule on said 110 end having a bore; a nut in said nut-receiving socket covered by said ferrule; and a bolt in said hole and bore and having its threaded end in said nut.

8. A plug of elongated transverse section 115 comprising a pair of chambered complements having reduced ends and wide meeting faces extending to the side and end edge faces of the plug; said plug having transverse outer and inner bolt holes provided with nut-receiving and head-receiving end-sockets and intersecting said faces, passing through the intramarginal part of the plug, the outer hole passing through the reduced ends; a ferrule on said ends having a counterbore; a nut 120 in said nut socket of the outer hole covered over, hidden and held against removal by said ferrule; a bolt in said outer hole having its head received in said counterbore and its threaded end in said nut and terminating 125 130

short of the ferrule; and a clamping bolt received in said inner hole, the nut being held against removal in any direction by the complement and ferrule while the bolt is removed

6 entirely away from the plug.

9. A plug comprising a pair of complements; said plug having a bolt hole through the ends of the complements, one of said ends being provided with a recessed passage in its

10 outer face extending from the adjacent end of the complement to said hole; a ferrule on said end having a bore provided with a counter bore having an inward projection adapted

15 to pass through said passage into alignment with the hole; and a clamping bolt in said hole and bore.

10. A plug comprising a pair of comple-

ments; said plug having a bolt hole provided with a head-receiving end-socket and passing through the ends of the complements one 20 of said ends having a passage recess extending from the end face of the complement to the head-receiving end-socket of said end; a ferrule on said reduced ends; said ferrule having an inwardly projecting counter bore 25 adapted to pass through said passage recess into the head receiving socket as the ferrule is applied and to register with said hole; a bolt in said hole and bore; and a nut on the threaded end of said bolt.

30

Signed at New York in the county of New York and State of New York this 26 day of July, A. D. 1926.

ELLIOTT CLEMENCE.
